UNITED STATES PATENT OFFICE.

JAN BRONS, OF APPINGEDAM, NETHERLANDS, ASSIGNOR TO NAAMLOOZE VENNOOT-SCHAP APPINGEDAMMER BRONSMOTORENFABRIEK, OF APPINGEDAM, NETHERLANDS.

ROTARY PUMP.

Application filed February 5, 1927, Serial No. 168,257, and in the Netherlands December 28, 1925.

The invention relates to a rotary pump of the type in which the vanes rotate about bosses, which are mounted concentrically with regard to the cylinder-axis and which 5 are connected to the cylinder-covers. The vanes are driven by a rotor which is mounted eccentrically within the pump-casing. The rotary pumps hitherto constructed in this way however possess the disadvantage 10 that there will be great wear on the edges of the vanes moving along the cylinder walls, so that these pumps soon become impracticable.

In order to remove these difficulties these 15 pumps according to the invention are so constructed that by a combination of constructional particulars the wear during use is diminished considerably.

These constructional particular features 20 are:

(1) That the driving rotor is composed of two or more parts and the driven vanes of one single piece.

(2) That the parts, of which the rotor 25 consists, are connected together and mounted on a shaft, which lies eccentrically within the cylinder, in the space between the bosses, about which the vanes rotate.

(3) That the vanes are supported on two 30 sides. As the rotor forms the element that drives the vanes and is driven by the eccentric shaft, on which the rotor is mounted, when this shaft turns with uniform velocity, the rotation of the rotor will be uniform. 35 However, as at each full rotation another point of the driven vanes comes into contact with the rotor, the vanes, the extremities of which move along the cylinder-walls, do not possess a uniform velocity. While 40 however according to the invention the vanes are made of one single piece, which is possible as the rotor consists of two or more parts, it is possible to keep the mass of the vanes very small, so that the difficulty with 45 the irregular velocity along the cylinder-walls is reduced to a minimum.

Furthermore according to the invention the vanes are supported at two sides, thereby preventing deviation of the vanes and 50 disintegration of the pump.

In order to effect this kind of support of the vanes the parts of the rotor according to the invention are connected together and

to the shaft, which lies eccentrically in the cylinder, in the space between the bosses. 55

In the drawing a preferred form of a rotary pump according to the invention is illustrated.

Fig. 1 is a cross-section and Fig. 2 a longitudinal section of the pump. 60

In the pump-cylinder 1 there is a shaft 2, on which the two parts of the rotor 3 are mounted. The connection of these parts to each other and to the shaft 2 is effected by means of the screw-bolts 4 and takes place 65 in the space between the bosses 5 and 6 which extend into the rotor and which are fastened to the cylinder-covers 7 and 8 or are cast with them. On the boss 5 the rings 9 and 11 are rotatably mounted and on the boss 70 6 the rings 10 and 12.

The vane 13 is connected to the rings 9 and 10 or it forms one single casting with them, and the vane 14 is similarly connected to the rings 11 and 12. The vanes are therefore supported on two sides by the bosses. 75 The vanes pass through the space between the extreme outer edges of the cylinder-parts of the rotor.

Of course the vanes can be connected to 80 the rings 9, 12 and 10, 11 instead of to the rings 9, 10 and 11, 12 so that there is a two-sided support, in which way there will be no one-sided deviation and extra wear.

I claim:

1. In a rotary pump, a cylindrical casing, said casing being provided on each of its side walls with a boss, said bosses being in axial alignment and disposed concentrically to the axis of said casing, a rotor comprising a plurality of segmental portions, a shaft mounted eccentrically to said bosses, said rotor being secured to said shaft between the bosses, and a plurality of rings surrounding each of said bosses, each of said rings having a radial vane integral therewith, said vanes projecting through an opening formed between adjacent segments of said rotor at opposite sides thereof. 85

2. In a rotary pump, a cylindrical casing, 100 said casing being provided on each of its side walls with a boss, said bosses being in axial alignment and disposed concentrically to the axis of said casing, a rotor comprising a plurality of segmental portions, a shaft mounted eccentrically to said bosses, said

rotor being secured to said shaft between the bosses and a plurality of rings surrounding each of said bosses, each of said rings having a radial vane integral therewith, said vanes projecting through an opening formed between adjacent segments of said rotor at opposite sides thereof, the vane on a ring placed on one of said bosses form-

ing with a vane on a ring placed on the other of said bosses a width equal to the inside width of the pump casing. 10

In testimony whereof I have signed my name to this specification.

Amsterdam, this 24th day of January 1927.

JAN BRONS.
